UNITED STATES PATENT OFFICE.

WALTER E. HORTON, OF ARLINGTON, AND ABRAHAM CARO, OF DORCHESTER,
MASSACHUSETTS.

DESIGN FOR A DRAWBOLT.

Application filed January 14, 1928. Serial No. 24,882. Term of patent $3\frac{1}{2}$ years.

To all whom it may concern:

Be it known that we, WALTER E. HORTON and ABRAHAM CARO, citizens of the United States, residing at Arlington, county of Middlesex, and Dorchester, county of Suffolk, Commonwealth of Massachusetts, respectively, have invented a new, original, and ornamental Design for Drawbolt, of which the following is a specification, ref-

erence being had to the accompanying drawing, forming part thereof.

Fig. 1 is a perspective view of our drawbolt showing our new design.

We claim:

The ornamental design for a drawbolt as shown.

WALTER E. HORTON.
ABRAHAM CARO.
